UNITED STATES PATENT OFFICE

EARL G. PORTS, OF WOODSIDE, NEW YORK, ASSIGNOR TO INTERNATIONAL COMMUNICATIONS LABORATORIES, INC., OF NEW YORK, N. Y., A CORPORATION OF NEW YORK

HETERODYNE OSCILLATOR

Application filed March 7, 1931. Serial No. 520,783.

This invention relates to radio receiving systems and more particularly to systems adapted to receive signals of either damped or undamped oscillations.

5 It is one of the objects of this invention to provide a receiving system which, for one adjustment, will act as a regenerative amplifier system and, for another adjustment, will be adapted for heterodyne reception.

10 Another object is to provide a frequency selecting network wherein adjustment of a single tuning element in a frequency selecting circuit effects tuning control of a second circuit inductively coupled to the selecting circuit, and a third circuit, which is both inductively and conductively coupled to the said frequency selecting network.

These objects, and certain novel features 20 of the invention, will be pointed out with greater particularity in the appended claims. For a more complete understanding of my invention, reference may be had to the following description taken in connection with the accompanying drawing.

25 As shown in the drawing, I provide an antenna 1, the periodicity of which may be determined by adjustment of condenser 2 in the tuned antenna circuit 2—3. Signals of radio frequency picked up by antenna 1 traverse the antenna tuned circuit 2—3. Variable coupling 4 having primary 3 and secondary 5 serves to transfer energy from antenna 1 to a frequency selecting network comprising inductances 5 and 6 and tuning condenser 7. 8

30 is a connection from circuit 5—6—7 to common ground lead 9. Connection 8 may contain condenser 18 as hereinafter explained. Coupling 10, comprising coils 6—11—12, is so arranged that the inductance coil 6 of the 40 tuned frequency selecting circuit 5—6—7 has an external field capable of providing sufficient coupling through coils 11 and 12 to determine, electrically, the frequency of the units associated with coils 11 and 12.

45 The electron discharge device 13 having filament 14, grid 15 and plate 16 is of the well-known type and is adapted to act as an oscillator or regenerative amplifier by controlling plate feed-back connection 17 by means of 50 condenser 18. A source of voltage 19 is con-

nected to plate 16 through radio frequency choke 20. Although condenser 18 is shown in its preferred position in lead 17, it is possible to have the regeneration control connected to the tuned selecting circuit 5—6—7 through 55 connection 8 to ground 9, as shown by the dotted lines in the figure, in which case, condenser 18 in the plate feed-back would be replaced by a conductive connection. I find, however, that with the condenser in its preferred position, regeneration is more easily controlled at the higher frequencies by eliminating the effect of mutual and distributed 60 capacities incident to the actual construction of coils 6, 11 and 12. 65

Detector 21 is preferably of the thermionic type and comprises control electrode 22, filament 23 and plate 24 as shown. A telephone or signal recording device 25 having by-pass condenser 26 associated therewith is connected in circuit with detector plate 24. Source 27 supplies energy to device 25. It is, of course, understood that any number of stages of audio amplification, not shown, may be placed intermediate the detector 21 and signal recording device 25. 70

By adjustment of condenser 18 to a point just below the point of oscillation, tube 13 will act as a regenerative amplifier for radio frequency oscillations, the frequency of the 80 amplified currents induced in coil 11 through inductance 6 being controlled, by reason of close coupling 10 of coils 6—11—12, by adjustment of condenser 7 in the tuned frequency selecting circuit 5—6—7. 85

For the reception of continuous (undamped) wave signals, by the heterodyne principle, the value of condenser 18 must be increased to the point where oscillation has just commenced, in which case the frequency 90 of the oscillator 13 would be governed by the frequency of the tuned selecting circuit 5—6—7.

Incoming signals will be passed on to coil 11 and thence to the grid 22 of detector 21 along with the locally generated oscillations, and in the detector 21 the resulting "beat" or difference frequency will cause current of audio frequency to flow through the following amplifier or telephone receiver. 100

Thus, no tuning condenser is necessary directly in grid of the detector, since tuning is accomplished in the frequency selecting network in circuit with the plate circuit of the oscillator.

Since the frequency of the local oscillator must differ from the frequency of the incoming signal by an amount corresponding to an audio frequency, it is necessary to slightly 10 "detune" circuit 5-6-7. The detuning necessary for "beat" reception is not sufficient to reduce, materially, the amplitude of the incoming waves, and by virtue of the heterodyne principle, the resultant audio frequency 15 amplification is materially greater than if the incoming signals were of damped variety and the heterodyne principle not utilized.

What is claimed is:

1. In a radio receiving system adapted to 20 receive signals of either damped or undamped waves, an electron discharge device having input and output circuits, a tuned frequency selecting network having an output circuit, a detector having an input circuit, inductances 25 individual to each of said input circuits, an inductance common to said output circuits, all of said inductances being coupled together, and a variable condenser in circuit with said first output circuit and said frequency selecting network for controlling the 30 operation of said electron discharge device.

2. In a radio receiving system adapted to 35 receive signals of either damped or undamped waves, an electron discharge device having input and output electrodes, a tuned frequency selecting network having an output circuit, a feed-back connection between said output electrode and said frequency selecting network, a detector having an input 40 circuit, inductances individual to said input electrode and said input circuit, and an inductance common to said output electrode and said output circuit, all of said inductances being coupled together, and means for 45 controlling the amount of energy in said feed-back connection.

3. An arrangement as claimed in claim 2, characterized in that, said means is a condenser included serially in said feed-back 50 connection.

4. An arrangement as claimed in claim 2, characterized in that, the said means is a condenser having one terminal connected to 55 said frequency selecting network, and the other connected to the output electrode of the said electron discharge device.

5. A radio receiving system adapted to receive signals of either damped or undamped waves, comprising an antenna, a tuned frequency selecting circuit having a first and a second inductance, said first inductance being coupled to said antenna, a detector having an input inductance, an electron discharge device having an input inductance 60 and an output circuit inductance, said output

inductance and said second inductance being common to said frequency selecting circuit and said output circuit, means for coupling said common inductance and said input inductances together, means for producing oscillations in all of said inductances, means in said frequency selecting network for controlling the frequency of said oscillations, and a variable condenser in electrical association with said output circuit and said frequency selecting circuit for controlling regeneration in said electron discharge device. 70

6. In a radio receiving system adapted to receive signals of either damped or undamped waves, an electron discharge device having input and output circuits, a tuned frequency selecting network having an output circuit, a detector having an input circuit, inductances individual to each of said input circuits, an inductance common to said output circuits, all of said inductances being coupled together, means for producing oscillations in all of said inductances, and a variable condenser in said frequency selecting network for controlling the frequency of said oscillations. 75

7. In a radio receiving system adapted to receive signals of either damped or undamped waves, an electron discharge device having input and output circuits, a tuned frequency selecting network having an output circuit, a detector having an input circuit, inductances individual to each of said input circuits, all of said inductances being coupled together, and variable means in circuit with said first output circuit and said frequency selecting network for controlling the operation of said electron discharge device. 80

8. The combination in a radio receiving system, of an antenna circuit including an inductance, a tuned frequency selecting circuit comprising a first and a second inductance, the said first inductance being inductively coupled to said antenna inductance, an electron discharge device having input and output circuits, a detector having an input circuit, inductive means coupling said inductance and said input circuits, and a connection from said output circuit to said tuned frequency selecting circuit. 85

9. The combination in a radio receiving system, of a tuned antenna circuit including an inductance, a tuned frequency selecting circuit comprising a first and second inductance, the said first inductance being inductively coupled to said antenna inductance, an electron discharge device having input and output circuits, an inductance in said input circuit, a detector having an inductance in its input circuit, said second inductance in said tuned frequency selecting circuit and the inductances in said input circuits of the electron discharge device and of said detector being inductively coupled together, and a 90
